M. F. BIERSDORF

LIQUID SPRAYER

Filed Oct. 1, 1921

UNITED STATES PATENT OFFICE.

MATHEW F. BIERSDORF, OF LOS ANGELES, CALIFORNIA.

LIQUID SPRAYER.

Application filed October 1, 1921. Serial No. 504,750.

To all whom it may concern:

Be it known that I, MATHEW F. BIERSDORF, a citizen of the United States, residing at Los Angeles, in the county of Los Angeles and State of California, have invented new and useful Improvements in Liquid Sprayers, of which the following is a specification.

This invention relates to a liquid sprayer and has for its object to provide a simple and durable construction in which the parts can be readily taken apart so as to clean the same and also to provide a construction which will allow the sprayer to be easily operated.

Other objects and advantages will be seen and the invention readily understood from the following description of the accompanying drawings in which:

20 Fig. 1 is a view showing a liquid tank and air supply with my improved sprayer connected to the same.

Fig. 2 is an enlarged longitudinal vertical section of the sprayer.

25 Fig. 3 is an enlarged detailed fragmentary section of the needle valve and cap.

My improved sprayer, in a preferred embodiment, comprises substantially a straight tubular body 1 having a plug 2 mounted 30 within the tube 1; and packing rings 3 are preferably mounted in grooves formed in the periphery of the plug so as to prevent leaking between the plug and the tube. In this embodiment, a straight sleeve 4 projects 35 forwardly from the plug 2 and is in axial alignment with a central bore 5 in the plug 2. Adjustably screw threaded on the forward end of the member 1 is a nozzle cap 6 delimiting a chamber and having a central 40 opening 7 extending forwardly from an enlarged recess 8. A valve seat is formed in the opening 7 in the cap by placing a disk 9 of relatively softer material therein and a nut 10 shown as provided with an aperture 45 of substantially the same diameter as the opening 7 and as having threaded engagement with the cap is adapted to hold the disk 9 in position. A tapered aperture is formed in the disk and is adapted to be 50 closed by the needle valve 11 which projects rearwardly through the bore 5, a packing gland 12, and slidably journaled in a bearing member 13 suitably held in a tubular member 14 extending rearwardly from 55 the member 1 and suitably fastened thereto

as by rivets 15, members 1 and 14, together with the plug 2, having a common axis, and constituting the body of the nozzle.

The means for actuating the valve stem, 60 comprises in the present embodiment, substantially a lever 16 pivotally connected as at 17 to a link 18 which is pivotally connected as at 19 to the tubular member 14 and projecting downwardly from the lever 16 is an actuating handle 20. A spring 21 65 surrounds the valve stem and abuts the bearing member 13 at one end and a cup 22 at its other end, which cup has engagement with the stem as by a pin 23 positioned on the rearward side of the same and has engagement with the lever 16 as by a curved surface 24 formed on the opposite side of the cup and a vertical slot 25 is formed in the lever so as to allow the rod to pass 70 through the same and it is thus seen that when the handle 20 is pushed forwardly the valve stem will be pulled back out of engagement with the aperture of the disk, 9, the needle 11 being shown as extending straight through the nozzle to project therefrom at either end, although engaged within said nozzle by actuating means.

Projecting downwardly from the member 1 is a short annular extension 25' upon which is screw threaded a downwardly projecting hollow handle 26. Positioned within the handle shown as extending substantially at right angles to the body of the nozzle are water and air conduit tubes 27 and 28. Screw threaded into the lower portion of the plug 2 and communicating with the axial bore 5 is a conduit 29 leading from the water conduit 27. An air conduit 30 communicates with the conduit 28 at one end and terminates in the annular space 95 formed around the sleeve 4.

Connected to the conduits 27 and 28 are hose 31 and 32 connected respectively to a water supply pipe 33 and an air supply pipe 34 which has any suitable valve controlling 100 means 35 positioned therein and the pipe 33 communicates with a liquid reservoir 36 which has a drain pipe 37 and an inlet pipe 38, the inlet from the latter being suitably controlled by any ordinary float construction as shown at 39. The air pipe 34 communicates with the upper portion of the reservoir as by a pipe 40.

Thus in the operation, air pressure from any suitable source (not shown), is forced 110

into the reservoir which causes the liquid to be forced out through the pipe 33, hose 31, up through the conduit 27, out through the straight sleeve 4 and through the aperture 5 in the disk 9 when the handle 20 is pushed forward. At the same time air will pass down through the pipe 34, hose 32, conduit 28 and into the annular space or chamber surrounding the sleeve and out through the 10 aperture in the disk 9, which will cause the liquid to be sprayed which also passes through the aperture.

Various changes may be made in the details of construction, without departing 15 from the spirit of my invention as set forth in the appended claims.

What is claimed is:

1. A liquid sprayer comprising a tubular member to which is secured a hollow handle, a plug in the said tubular member having liquid and air conduits, a nozzle cap adjustably mounted on the forward end of said tubular member, a valve stem slidably mounted in said plug and adapted to close 20 said nozzle, air and liquid pipes extending through said hollow handle and having communication with said conduits, said pipes being supported by said plug, and means for actuating said valve stem.
2. A liquid sprayer comprising a tubular member, air and liquid conduits in said member terminating in a common chamber, a nozzle cap having an aperture leading from said chamber, an apertured disc of 25 softer material in said aperture, a nut for securing said disc, a needle valve for controlling the flow through said nozzle cap, the needle of said valve being seated on said disc and adapted to project through said disc in said nozzle cap, and means for actuating said valve.
3. A liquid sprayer comprising a tubular member, a plug having an axial opening

mounted in said member, a sleeve projecting forwardly from said plug and having 45 a co-axial opening, a nozzle cap mounted on the forward end of said tubular member, a valve stem slidably mounted in said plug and adapted to close an outlet extending through said nozzle cap only, said stem projecting rearwardly through both said plug and a tubular extension, valve actuating mechanism mounted on said tubular extension, and air and liquid conduits communicating with the interior of said plug. 55

4. A sprayer comprising a longitudinal body member, a nozzle cap carried on one end of said member and delimiting a chamber, a handle projecting downwardly substantially at right angles from said body 60 member, air and liquid conduits positioned within said handle and communicating with said chamber, a spring seated valve provided with a stem longitudinally shiftable through said body member, disc of soft material secured as a valve seat in said nozzle cap, said stem being adapted to close said nozzle cap by contact with said disc, and means for actuating said stem. 65

5. A sprayer comprising a tubular body, 70 a plug positioned therein and provided with conduits, a nozzle cap secured on one end of said tubular body and provided with an aperture, a valve seated in said aperture, a tubular extension secured to the other end 75 of said tubular body, valve actuating means secured to said tubular extension, a handle secured substantially at right angles to said tubular body, and pipes within said handle, 80 said pipes being secured to the plug within said tubular body and connected with the respective conduits therein.

In testimony whereof I have signed my name to this specification.

M. F. BIERSDORF.
